CLAIM

The ornamental design for a fishing rod storage device, as shown and described.

DESCRIPTION

FIG. 1 is a perspective view of a fishing rod storage device showing our new design;

FIG. 2 is an enlarged front view thereof;

FIG. 3 is an enlarged rear view thereof;

FIG. 4 is a top view thereof;

FIG. 5 is a bottom view thereof;

FIG. 6 is a left side view thereof; and,

FIG. 7 is a right side view thereof.

The broken lines shown are included for the purpose of illustrating unclaimed subject matter and forms no part of the claimed design.

1 Claim, 4 Drawing Sheets
